COIN LOCK

Adolph Wunderlich, Cleveland Heights, Ohio

Application May 11, 1937, Serial No. 141,949

2 Claims. (Cl. 194—74)

My invention is an improvement in coin locks, and relates more particularly to devices of this character in which mechanism operated by one coin placed in the lock obstructs or prevents the insertion of a subsequent coin until a predetermined cycle of operation of the lock has been performed.

One of the objects of my invention is to provide a coin lock of simple construction which is especially suitable for use on toilet doors and which when charged with a coin will permit the door to be opened and will not receive another coin until the lock is released from the inside.

Another object of the invention is to provide a coin lock of this character which is positive in operation and which is operable only by inserting one coin therein during each complete cycle of use.

Other objects and advantages of my invention will become more apparent from the following description of one embodiment thereof, reference being made to the accompanying drawing in which like reference characters are employed to designate like parts throughout the same.

In the drawing:

Figure 1 is a front elevation of a coin lock mechanism embodying my invention, and shows the relative positions of certain of the parts when a coin is first placed in the lock.

Figure 2 is a view looking in the direction of line 2—2 of Figure 1, and shows some of the lock casing in section.

Figure 3 is a view similar to that of Figure 1, and shows the second step in the operation of the lock, that is, when the outer knob is rotated to unlock the door.

Figure 4 is another similar view of the parts in their relative positions at the completion of the third step in operating the lock. In this view the bolt is returned to door locking position while the coin is retained within the lock mechanism, and an obstruction is moved to position to block or prevent the deposit of an additional coin therein. In this view the positions of the parts are such that the door is ready to be locked and the coin passage blocked.

Figure 5 is a section taken on line 5—5 of Figure 1.

When the door is shut, the coin is deposited in a receptacle, and in the final step or unlocking it from the inside, as by manipulating the inner knob, the obstruction is removed from the coin passage. The parts will then return to the substantial positions illustrated in Figure 1.

An emergency means (not shown) may be pro-

vided for unlocking the lock from the outside by means of a special key and without the use of a coin.

I will now proceed to describe in detail the embodiment of my invention illustrated in the accompanying drawing.

A suitable casing 1 is provided to enclose the operating mechanism and is formed along one side with a coin receiver 2 having a slot 3 through which the coin 4 enters the lock. The casing 1 has an opening on one side to receive a removably fixed plate 5 which preferably is screwed to the casing as at 6 and carries certain of the lock mechanism.

The lock bolt 7 is mounted to slide transversely within the casing and is projected, as shown in the device herein illustrated, to the right by means of a spring 8 which is compressible between the portion 9 of the bolt and a stop 10 secured to the plate 5. As seen in Figure 5 on the line 20 55 of Figure 1, the bolt is provided with an elongated slot 11, at the rear end of which is formed an arcuate groove 12 for receiving a portion of the circumference of the coin 4. The slot 11 is long enough so that under certain conditions and 25 when the coin 4 is released, it will be permitted to fall through the slot 11 and into the bottom of the casing 1.

The bolt is also provided with an inward bearing projection 13 which slides along the guide 30 14 on the plate 5.

This projection is engageable by an arm 15 which is operable by means of a knob 16 on the back of the lock. A stop 17 is carried by the plate 5 to limit the swing of the arm 15 in one direction, whereas its limit of motion in the opposite direction is limited by the abutment of the stop member 18 on the bolt with the stop 10 or by full compression of the spring 8.

The knob 19 is located on the "outside" of the lock, that is, its front face, and is keyed to a shaft 20 and a rocker arm 21 by means of a screw 22. The lower end of the rocker arm operates against a stop 23 and is normally pulled to the left in Figure 4 by means of the tension 40 spring 24 carried by the plate 5 at 25. The rocker arm also employs an arm 26 which projects upwardly and terminates in a head portion 27 having an arcuate groove 28 formed on its left hand edge. The purpose of this groove is to guide and 45 receive a portion of the circumference of the coin 4 as shown.

I have also provided a slidable member 29 which has portions cooperating with portions of the bolt and the head 27 of the arm 26 so that these 50 55

parts will move in unison in one direction when a coin is dropped into the receiver 2.

The slide 29 comprises preferably a rectangular body having indicia on its forward face such as the words "Vacant" and "In use" and is arranged so that the proper indicia will be displayed through the window 30 in the casing as the lock is being used.

The slide 29 is provided with a projection or guide 31 which operates in the groove or recess 32 in the plate 5 and is provided with a slotted coin passage 33 which lies directly under the coin slot in the coin receiver 2. The slide 29 is also slotted at 34 to receive the arm 35 operable by the inside shaft and knob 16 to return the slide to the right as in Figure 1.

If desired, the slide may have a link connection as at 36 with a counter 37 which it operates to register the number of times the lock is put through its cycle of operation or, in other words, to register the number of coins which have passed through and operated the lock mechanism.

According to my invention, I have made a distinct improvement by providing for means whereby when a coin has been placed in the lock and its cycle of operation has been started, the insertion of a subsequent coin through the receiver 2 to the slide 29 is prevented until the complete cycle of operation of the lock is accomplished. In carrying out this improvement I provide a coin rejector which preferably consists of a member 40 freely pivoted at 41 to operate in the passageway of the receiver 2. This member is provided with a straight side 42 which engages the top or one side of the slide 29. When the slide is to the right as in Figure 1, the member 40 lies in the position shown in that figure and against the left hand side of the slide.

As the slide moves to the left, as in Figure 3, the flat side of the member 40 rides upon, and lies along the top of the slide 29. It is to be noted that the upper portion of the member 40 is cam shaped or enlarged so that when the member is in the position shown in Figures 3 and 4, its enlarged or head portion 43 is projected sufficiently into the slot 3 that it will prevent the passage of another coin through this slot or passage. However, when the slide is to the right, as in Figure 1, the enlarged head portion 43 of the member 40 is removed from the slot 3.

As will be seen from the drawing, the member 40 is freely pivoted and operates by gravity to remove its head from the slot 3 when the slide 29 is moved to the right.

I will now proceed to describe briefly the complete cycle of operation of the lock as applied to the door of a private toilet, or the like.

The lock is assembled on the door so that the knob 19 will be located on the outside of the door and of course the door frame will be provided with the usual complementary bolt plate.

Figure 1 represents the lock thus applied to the door, and in this view a coin 4 has been inserted in the slot 3 of the receiver. The coin passes through the slot 3 unobstructed, and comes to rest in the position indicated, that is, with part of its circumference resting in the groove 12 and another part resting against the groove 28 of the arm 26.

In this position, the coin lies partly within the slide 29 and partly within the bolt 7 and thus affords a driving connection between the slide and the bolt when the knob 19 is turned to throw the arm 26 to the left in Figure 1.

As this arm is rotated to the left, the coin, the

slide, and the bolt are also moved to the left, and the door may be opened. Simultaneous with this movement of the parts, as illustrated in Figure 3, the member 40 is rotated to the position shown in Figure 3 to obstruct the slot 3 with its enlarged head 43, thus preventing the insertion of another coin through the slot.

As the knob 19 is released, the parts will assume the positions shown in Figure 4, the slide 29 remaining at the left, and the bolt, coin, and arm 26 returning to the right by virtue of the action of the springs 8 and 24. Now, as the door is closed, the bolt end engaging the bolt plate (not shown) in the door frame will be forced again to the left momentarily against the compression of the spring 8. This action will permit the coin to be released by the arm 26 which under these conditions remains to the right, and the coin will pass downwardly through the slot 11 of the bolt and will be deposited in the bottom of the casing 1.

It will be noted that the door is now closed, the initial coin has been deposited in the receptacle or casing, and the passage 3 is still obstructed by the head 43 of the member 40.

When the door is to be opened from the inside by turning the knob 16, the bolt 7 is retracted by means of the arm 15 moving to the left in Figure 4 against the portion 13 of the bolt. At the same time the upper arm 35, likewise operated by the knob 16, is swung to the right against the right hand portion of the slide to move the slide to the right.

Movement of the slide to the right allows the freely pivoted member 40 to assume the position shown in Figure 1 to remove the obstruction in the slot 3.

Thus the cycle of operation is complete and may be repeated in a like manner by inserting another coin in the slot 3 after the door has been closed again.

Of course, it is understood that as the slide moves to the left, the counter will register this action and likewise the word "Vacant" in the window 30 will be replaced by the words "In use".

Various changes in the details of construction and arrangement of parts may be made without departing from the spirit of my invention or the scope of the appended claims.

I claim:

1. A coin lock comprising a housing having a coin receiving slot therein, a bolt slidable in said housing and spaced below said slot, said bolt having an elongated slot therein terminating at one end in a coin seat, a slide operable in the space between said coin receiving slot in the housing and said bolt, said slide having an opening therein to pass a coin from the receiving slot to the said coin seat in the bolt slot when the slide is in one extreme limit of movement, said coin seat being arranged to support a coin in the bolt so that the upper portion of the coin will project into the opening of the slide, a bolt operating lever in said bolt slot and operable to engage a coin supported in said coin seat and projecting into said slide opening, to slide said bolt and said slide simultaneously in one direction, means for releasing said coin from said bolt when the bolt is moved in the opposite direction, and a coin rejector comprising a loosely hung member pivotally supported in said housing, near said coin receiving slot and normally depending in the path of movement of said slide when the slide is in coin receiving position, said rejector having a portion projecting into said

coin receiving slot to block the same when said slide is moved toward its opposite limit of movement.

2. A coin lock comprising a housing having a coin receiving slot therein, a coin rejector operable in said slot, a slidable bolt, a slidable member between said bolt and said slot, said bolt and slidable member having communicating passages to receive a coin from the said slot, means to

trap a coin between said bolt and slidable member, a member pivotally operable to engage a coin trapped therein to move said bolt and slide as a unit in one direction, said coin rejector comprising a member loosely pivoted in the housing near 5 said slot, said rejector being operable by said slide to block said coin receiving slot when said slide has been so moved.

ADOLPH WUNDERLICH.
